UNITED STATES PATENT OFFICE.

FRANK A. VOSSENBERG, OF STAMFORD, CONNECTICUT, ASSIGNOR TO THE YALE & TOWNE MANUFACTURING COMPANY, OF STAMFORD, CONNECTICUT.

LOCK.

Application filed April 22, 1925. Serial No. 25,084.

This invention relates to improvements in locks and more particularly to those of the double-extension-bolt type, operable by a key.

- 5 One object of the invention is to so construct the lock that a single tumbler connected and movable with one of the bolts shall be operable to lock both bolts in either projected or retracted position.
- 10 With this and other objects in view, the invention consists in certain novel features of construction and combination of parts as hereinafter set forth and pointed out in the claims.

15 In the accompanying drawings;

Figure 1, is a plan view of a lock embodying my invention;

Figure 2, is a similar view, with the cover plate removed and the bolts locked in retracted position;

Figure 3, is a view similar to figure 2, with the bolts locked in projected position;

Figure 4, is a sectional view on the line 4—4 of Figure 2;

25 Figure 5, is a perspective view of the tumbler, and

Figure 6, is a view showing the bolts.

In the construction of my improved lock, I employ a casing 1 having side and end walls 2, 3 and a cover plate 4, the latter having depressed portions 5 to act as guides and retaining means for bolts 6, 6, which are mounted to slide on the bottom of the casing and guided by the side walls 2 of the latter,—the outer ends of said bolts being adapted to project through suitable openings in the end walls 3 of the casing. The casing may also be provided with stops 8, 8 to limit the inward throw of the bolts and shoulders 9 on the bolts cooperate with end walls of the casing to limit the outward movement of said bolts.

Each bolt is provided intermediate its ends with a key notch 10, and at respective sides of such notch, the inner edge of each bolt is recessed as at 11 for the accommodation of a flat key 12 which enters between the bolts. A revoluble key guide 13 is mounted in the cover plate 4 and the casing 50 may be provided with a hole or socket for the accommodation of a projection 14 on the end of the key. Between the key notch 10 and the outer end portion 7 of each bolt 6, spaced notches 15, 16, (each of which may 55 be made flaring) and between the key notch

10 and the inner end, each bolt is provided with a notch 17, which latter may also be made flaring.

A tumbler 18 is disposed over the bolts and provided at one end with a head 19 which may have a rounded edge 20 to ride against one of the side walls 2 of the casing. The headed end of the tumbler is provided with a lateral lug 21 which loosely enters the flaring notch 16 in one of the bolts. The other end of the tumbler is provided with a finger 22 which normally engages one of the side walls of the casing, and this same end of the tumbler is provided with a lateral lug 23 to enter a notch 17 in one bolt 70 and a notch 15 or 16 in the other bolt, a spring 24 secured to the headed end of the tumbler and engaging a side wall 2 of the casing, serving to retain the tumbler in or returning it to position to lock both bolts. 75

From the construction and arrangements of parts above described, it will be seen that the tumbler 18 has pivotal connection with one of the bolts and that it is cooperable also with the other bolt in a manner to 80 have interlocking relation with the bolts to lock them in either projected or retracted position.

When the key is inserted in the space (afforded by the recesses 11) between the 85 bolts, and turned, its edge portions will engage in the key notches 10, and as the tumbler spans the key notch in one of the bolts, the key will engage said tumbler and swing the latter sufficiently on its pivotal connection with one of the bolts to cause the lug 23 to move completely out of one of the notches (15 or 16) of the other bolt. Continued turning of the key will now cause the two bolts to slide respectively 90 in opposite directions, the tumbler moving with the bolt with which it is pivotally connected. When the bolts are in retracted position, a notch 17 in one bolt will align with a notch 16 in the other bolt, so that 100 the lug 23 on the tumbler will project from the notch 17 in one bolt and enter the notch 16 in the other bolt, thus interlocking the two bolts as shown in Figure 2. When the bolts are in projected position, interlocking 105 will be effected by the tumbler lug 23 in cooperation with the notch 17 in one bolt and the notch 15 in the other bolt (said notches being then in alignment) as shown in Figure 3.

Various slight changes might be made in the details of construction of my invention without departing from the spirit thereof or limiting its scope and hence I do not 5 wish to restrict myself to the precise details herein set forth.

Having fully described my invention what I claim as new and desire to secure by Letters-Patent, is:—

- 10 1. In a lock, the combination with a casing, and bolts mounted therein to slide respectively in opposite directions, of a single key controlled tumbler having pivotal connection with one of said bolts and cooperable with the other bolt, whereby said bolts will be locked against relative movement either when in projected or retracted position.
- 20 2. In a lock, the combination with a casing, of relatively movable sliding bolts mounted therein, said bolts having opposed key engaging portions, a spring-pressed, key-controlled tumbler having pivotal connection with one of said bolts, and means whereby said tumbler has cooperative relation with the two bolts to interlock them in either projected or retracted position.
- 30 3. In a lock, the combination with a casing, of two relatively movable sliding bolts mounted therein, and having opposed key engaging portions, one of said bolts having a notch between the key engaging portion and the inner end of said bolt, and the other bolt having two notches between its outer end and its key engaging portion, a spring-pressed key-controlled tumbler having pivotal connection with the first-mentioned

bolt and having a lug to enter the notch therein, said lug also entering one of the other of the notches in the other bolt to lock 40 the bolts in either projected or retracted position.

4. In a lock, the combination with a casing and relatively movable sliding bolts having opposed key engaging portions, of a 45 spring-pressed key controlled tumbler having pivotal connection with one of said bolts and cooperable with the bolts to interlock them.

5. In a lock, the combination with a casing and relatively movable sliding bolts having opposed key engaging portions, of a 50 spring-pressed key controlled tumbler having pivotal connection with one of said bolts and cooperable with the bolts to interlock 55 them, said tumbler having portions at each of its ends to engage and ride against a side wall of the casing.

6. In a lock, the combination with a casing and relatively movable sliding bolts having opposed key-engaging portions, of a 60 spring-pressed key controlled tumbler having a head portion at one end, pivotally connected with one of said bolts and adapted to ride against a side wall of the casing, said 65 tumbler having a finger at its other end to ride against said side wall of the casing and also having a lug adjacent to said finger, said bolts having part with which said lug is cooperable to lock said bolts in either projected or retracted position.

In testimony whereof I have signed this specification.

FRANK A. VOSSENBERG.
